UNITED STATES PATENT OFFICE.

JOHN L. LEAVITT, OF GRANT, TERRITORY OF NEW MEXICO.

DESIGN FOR A HANGING STAND.

SPECIFICATION forming part of Design No. 18,972, dated March 19, 1889.

Application filed February 19, 1889. Serial No. 300,492. Term of patent 7 years.

To all whom it may concern:

Be it known that I, JOHN L. LEAVITT, a citizen of the United States, residing at Grant, in the county of Valencia and Territory of New Mexico, have invented and produced a new and original Design for a Hanging Stand, of which the following is a specification, reference being had to the accompanying drawing, which represents a perspective view of my newly-designed hanging stand.

The leading feature of my design is the configuration and ornamentation of the base A of the stand, which is of dish shape on top, and as seen from its side presents the appearance of a series of flat rings or disks, b c d, of varying and diminishing sizes, one below the other, so as to give to the whole base a circular stepped appearance in a downward direction. This base is ornamented on its exterior so as to represent a speckled-granite appearance. The stand is further embellished by chain-like ornaments e, falling in festoons from the

sides of the upper portion of the base to and below the latter and terminating above in ring-shaped ornaments f. The suspension-chains g converge upward from the base and connect above with a central suspension device, h, of globular form, with ring-shaped appendages i; but this suspension device may be otherwise shaped. 25 30

I claim—

The design for a hanging stand herein shown and described, the same comprising the base A, of circular contour and inverted stepped configuration on its sides, and presenting a speckled-granite-like appearance on its exterior, and further comprising chain-like ornaments e, falling in festoons at the sides of and below the base, as set forth. 35

JOHN L. LEAVITT.
